Primary Examiner — Catherine Tuttle(74) *Attorney, Agent, or Firm* — Kinney & Lange, P.A.(57) **CLAIM**

The ornamental design for a volleyball training platform, as shown and described.

DESCRIPTION

FIG. 1 is a perspective view of the volleyball training platform showing our new design in its erected position;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view of the volleyball training platform showing the design in a collapsed position;

FIG. 9 is a front elevational view thereof;

FIG. 10 is a rear elevational view thereof;

FIG. 11 is a left side elevational view thereof;

FIG. 12 is a right side elevational view thereof;

FIG. 13 is a top plan view thereof; and,

FIG. 14 is a bottom plan view thereof.
